United States Patent Office.

J. B. COLLIN, OF ALTOONA, PENNSYLVANIA.

Letters Patent No. 95,196, dated September 28, 1869.

IMPROVED RAILWAY-CAR JOURNAL-BOX.

The Schedule referred to in these Letters Patent and making part of the same.

To all whom it may concern:

Be it known that I, J. B. COLLIN, of Altoona, in the county of Blair, and State of Pennsylvania, have invented a new and improved Railroad-Car Journal-Box; and I do hereby declare that the following is a full, clear, and exact description thereof, which will enable others skilled in the art to make and use the same, reference being had to the accompanying drawings, forming part of this specification, in which—

Figure 1 represents a vertical longitudinal central section of my improved journal-box.

Figure 2 is a front view of the same.

Figure 3 is a detail horizontal section of the same, taken on the plane of the line x x , fig. 1.

Similar letters of reference indicate corresponding parts.

My invention relates to an improvement in car-axle boxes; and consists in pivoting to the journal-box a spring-plate with corrugated ends to lock under a pair of hooks.

A, in the drawing, represents a journal-box, of suitable shape and size.

B is the lid, hinged to the box by a pin, a .

The lid is so formed that its middle portion is higher than the edges, as shown in fig. 1.

To this raised middle portion is, by a pin, b , pivoted a spring-bar or plate, C, which has longitudinally-corrugated ends, as indicated in figs. 2 and 3.

On the box are, above and below the lid, formed projecting hooks c d , which, with their bills, point toward the pivot b .

The ends of the plate C are, in order to lock the lid, put under the hooks c d , as in fig. 2.

The hooks are V-shaped in their cross-section, and fit, when the lid is closed, into grooves formed at the ends of the plate C, as shown, thereby holding said plate in position.

The plate springs sufficiently to let its raised portions pass the hooks when to be opened or locked.

In the ordinary boxes, the oil frequently oozes out between the axle and the rear opening of the box, and does then trickle down on the wheel upon the rail. To prevent this, I have provided a forward-inclined pipe or aperture, e , in the lower back part of the box, to take the oil that flows over out, and to conduct it away from the wheel.

D represents a transverse rib, arranged in the box, under the front opening of the same, to prevent the packing from being thrown up against the lid, and from forcing the same open.

Having thus described my invention,

I claim as new, and desire to secure by Letters Patent—

The spring-plate C, pivoted to the lid B of a journal-box, and provided with corrugated ends to lock under the hooks c d , substantially as and for the purpose herein shown and described.

J. B. COLLIN.
